THERMOSTATIALLY CONTROLLED OIL BURNER

Lynn Otis Selby, Hartford, Conn., assignor to The Sparmal Engineering Corporation, a corporation of Connecticut

Application October 9, 1936, Serial No. 104,808

20 Claims. (Cl. 236—99)

My invention relates to thermostatically controlled oil burners.

It has among its objects to provide an improved thermostatically controlled oil burner and one especially adapted to use in refrigerators of the absorption type. A further object is to provide an improved thermostatically controlled valve for supplying fuel to the burner of such a refrigerator having a movable valve element directly actuated by the thermo-responsive element to increase the supply of fuel to the burner upon expansion of the thermo-responsive element and decrease the supply upon contraction thereof in a new and improved manner. A still further object is to provide an improved thermostatically controlled valve for controlling a distillate burner. Another object is to provide such an improved valve especially adapted for use in an absorption type refrigerator and having, in a unitary structure with the temperature controlled valve, both improved high and low flame adjusting means. A still further object is to provide an improved thermostatically controlled valve of the plunger type in which the thermally expansible element is supported directly on the valve housing. Another object is to provide an improved thermostatically controlled valve in which the high and low flame adjusting means are concentric with the temperature controlled valve. Other objects are to provide an improved thermostatically controlled valve which can be cheaply and easily manufactured, which occupies a minimum of space, and which can be installed in the limited space available in existing refrigerators of the oil burning type in place of the manually controlled valves now in use. These and other objects and advantages of my improved construction will, however, hereinafter more fully appear.

In the accompanying drawings I have shown for purposes of illustration several embodiments which my invention may assume in practice.

In these drawings—

Figure 1 is an elevation partly in section of an oil burning refrigerator equipped with my improvement, only those parts of the refrigerator being shown which are necessary to an understanding of the invention;

Fig. 2 is a full size sectional elevation of the thermostatically controlled valve of Figure 1;

Fig. 3 is a section on line 3—3 of Figure 2;

Fig. 4 is a section on line 4—4 of Figure 2 with certain parts omitted;

Fig. 5 is a full size sectional elevation of a modified form of thermostatically controlled valve;

Fig. 5a is a plan view of the valve of Figure 5;

Fig. 6 is a full size sectional elevation of another modified valve construction;

Fig. 7 is a section on line 7—7 of Fig. 6;

Fig. 8 is a section on line 8—8 of Fig. 6;

Fig. 9 is an elevation, partly in section, of a construction, applicable to any of the above modified forms of valve, for connecting the valve plunger to the expansible fluid operated member of the thermostat;

Fig. 10 is a full size sectional elevation of still another modified thermostatically controlled valve;

Fig. 11 is an elevation of the plunger assembly of the valve of Fig. 10;

Fig. 12 is a sectional detail on line 12—12 of Fig. 10;

Fig. 13 is a full size sectional elevation of another modified form of thermostatically controlled valve;

Fig. 14 is an elevation of the plunger assembly of the valve of Fig. 13, and

Fig. 15 is a detail view somewhat similar to Fig. 9 showing a connection suitable for use with the valve forms shown in Figs. 10 and 13.

In these drawings, I have shown for purposes of illustration several forms of my improved thermostatically controlled valve, certain of which were disclosed and claimed in an application, Serial No. 75,991, filed April 23, 1936, of which the present application is a continuation in part. In all of the various forms shown, my improved valve A is adapted to control a distillate type oil burner B of a well known "Servel" refrigerator, indicated generally at C, and including the usual boiler, or generator, 1, freezing unit 2, fuel supply tank 3 and constant level float chamber 4 provided with a cover 4a, all in such manner as hereinafter described to enable improved results to be obtained never before obtainable in an oil burning refrigerator.

In this well known "Servel" construction, oil from the tank 3 is supplied through feed line 5 to chamber 4 and the oil is maintained at a constant level 4b in chamber 4 by means of a usual float valve 6 governed by a float 7, the usual safety trip bucket 8 and reset lever 9 being provided. The fuel is led from the constant level chamber 4 to the carbon leg 10 of the burner through a feed line 11 having a usual gravity operated high temperature cut-off valve 12 controlled by a fusible link 13 located adjacent the burner B. The chamber 4 is also provided on one side wall with a generally cylindrical valve hous-

ing, or socket, 14 forming a separate oil chamber, or well, 15 which is in communication with feed line 11 and which also communicates with the chamber 4 through a screw threaded passage 16 in the bottom wall of housing 14. In this construction it has hitherto been thought impossible to use a thermostatically controlled valve and necessary to use a manually controlled metering valve threaded into the passage 16 and having a manually adjustable control member projecting through the opening 16a in cover 4a by means of which the fuel supply to the burner B was governed.

In accordance with the present invention, the improved thermostatically governed control valve A for automatically regulating oil flow to the burner B is adapted to be threaded into passage 16, this valve A including an improved valve and thermostatically controlled means associated therewith in an improved manner and both of the same cooperating to enable an improved automatically operative temperature responsive control to be obtained for the first time in a refrigerator of this type.

In Figures 1-4, I have shown a preferred form of my improved thermostatically controlled valve A. As shown most clearly in Figures 2, 3 and 4, the valve casing 17 comprises a piece of cylindrical stock, the lower end 18 of which is reduced in diameter and threaded to be received in the passage 16 at the bottom of the oil well 15, a suitable gasket 19 forming a fluid tight closure for the oil well at this point and preventing fluid communication with the main float chamber 4 except through the valve, as hereinafter explained. The valve casing 17 is provided with a vertical plunger passage 20 terminating somewhat above the lower end of the casing and having a slightly enlarged threaded upper end portion 21. This passage bisects an intersecting horizontal passage 22 which communicates at one end with the well 15 and at its other end with the float chamber 4 through a series of passages 23, 24 and 25, as is shown most clearly in Figure 2. The cross section of the passage 22 is varied by a vertically reciprocable plunger 26 which is adapted to be reciprocated in the plunger passage 20 by expansible fluid actuated means herein-after described.

In this preferred form, the plunger 26 includes a generally cylindrical portion 26a having a close running fit in the plunger passage 20. An annular groove 27 is provided near the lower end of portion 26a forming a control portion 28 at the lower end of the plunger which is normally located in the transverse passage 22, as shown in Figure 2, and controls the passage of fluid through the valve as the annular groove 27 is moved more or less into register with the passage 22. The plunger 26 has a reduced upper end portion 30 threaded at 31 and forming an upwardly facing shoulder 32 located within the threaded portion 21 of the valve casing 17. The shoulder 32 cooperates with the lower end of a threaded sleeve 33 which surrounds and guides the upper end of the plunger. Sleeve 33 is formed with an upper hexagonal portion 34 to permit rotation of the sleeve to adjust the same vertically to vary the point at which the shoulder 32 of the plunger will engage the sleeve, thus adjustably limiting the extent of movement of the plunger in an upward direction. A set screw 35 (Figs. 1 and 3) is provided for holding the sleeve 33 in its adjusted position in which it determines the low flame or pilot adjustment of the burner.

10 A needle valve 36 is screw threaded into a passage 37 aligned with passage 23 in the valve casing 17 and intersects the horizontal passage 22. The passage 37 and the needle valve 36 are of somewhat larger diameter than passage 23, thus providing a seat 37a (Fig. 4) at the upper end of the latter passage for the tapered end of the needle valve. A hexagonal upper end portion 38 is provided for the rotation of the needle valve 36 for adjusting the same relative to its seat, thereby to establish the maximum flame adjustment for the burner.

15 The reciprocation of the plunger 26 in the plunger passage is governed by expansible fluid operated means including an expansible wafer 40, the upper end 41 of which carries a flexible supporting diaphragm 42 which has its periphery clamped by screws 42a between upper and lower complementary housing and supporting members 43 and 44. The expansible wafer 40 is accurately centrally located within the housing by the provision of an upstanding annular flange 45 on housing member 44 within which the diaphragm 42 is closely received. The lower housing member 44 is formed with a depending cylindrical boss 46 having an axial passage in which a bushing 47 is located. The upper housing member 43 is also provided with an axial bushing 48 in which is threaded a stud 49 which, upon rotation in one direction, bears at its lower end on the hollow boss 50 formed on the upper end wall 41 of the expansible member and flexes the diaphragm 42 downwardly, thus depressing the wafer 40. The stud 49 is formed with an octagonal head which is received in an octagonal recess in an externally cylindrical member 51 secured to the stud by an axial screw 51a. Manual rotation of the stud 49 to control the position of the expansible member 40 is accomplished by a rotatable control button 52 movable over a suitable dial located on the refrigerator and a control cable 53, cooperating stops 53a and 53b being provided on the member 51 and casing 43 to limit the rotation of the stud.

20 The expansible member 40 is of a well known type adapted to contain an expansible fluid and communicates through a tube 54 extending into the hollow boss 50 with a temperature responsive element 55 located in the refrigerator compartment adjacent the cooling unit 2. It will be understood that the tube 54 and temperature responsive element 55 likewise contain expansible fluid and that the expansion and contraction of the fluid in element 55 is conveyed to and influences the expansible member 40. The plunger 26 is directly connected to the lower end wall 56 of the expansible member. To this end the lower wall 56 thereof has an integral depending stem 57, guided in the bushing 47, which is provided with a screw threaded recess 58 to receive the threaded portion 31 of the plunger. A knurled adjusting wheel 59 is initially threaded onto the plunger 26 and is fixed thereto by a lock nut 60 so that rotation of the wheel 59 will rotate the plunger relative to the stem 57 and adjust the plunger vertically relative to the wafer 40.

25 The expansible member 40 and its housing are supported above the plunger and in axial alignment therewith by means of a tubular supporting member 61 having a portion of its side wall intermediate its ends cut away to permit access to the wheel 59 and the high and low flame adjustments. The tubular member 61 has an enlarged lower end portion 61a which fits over a reduced cylindrical portion 62 at the top of the valve cas-

ing 17 and preferably is secured permanently thereto as by soldering or welding. The outer surface of the portion 61a is hexagonal and since it is located above the cover 4a serves as a wrench engaging portion for the valve casing, permitting the valve to be screwed into the threaded passage 16. The depending cylindrical boss 46 of housing member 44 is formed accurately to the bore in the upper cylindrical end 63 of member 61, a screw 64 being provided to prevent relative movement of the parts. As shown most clearly in Figure 3, an opening 65 is provided in the lower hexagonal portion 61a permitting access to the set screw 35.

As shown most clearly in Figure 2, a ball and socket connection 66 is provided between the plunger rod 30 and the portion 26a thereof, although this may be omitted if care is taken in the manufacture and assembly of the valve. Here it should also be noted that to prevent binding of the valve plunger the passage in the low flame adjustment sleeve 33 is slightly larger than the valve stem 30, thus eliminating any tendency for the plunger to bind due to misalignment of the expansible member and its support.

The plunger 26 is limited in its upward movement by the engagement of the shoulder 32 with the lower end of the low flame adjusting sleeve 33 previously referred to, the latter being vertically adjustable in the plunger passage 20 to vary the upper limit of movement of the plunger. As shown most clearly in Figure 2, a definite relation exists between the shoulder 32 on the plunger and the lower shoulder 29 formed by the groove 21, these shoulders being so arranged that the engagement of the lower end of sleeve 33 with shoulder 32 takes place when the control portion 28 of the plunger has almost completely cut off the passage 22 and the shoulder 29 is approaching the point at which it completely closes this passage, the sleeve 33 being adjusted to permit only a low flame orifice. It will also be understood that the adjustment of the needle valve 36 relative to the seat 37a determines the maximum volume of oil which can pass through passage 22 and thus constitutes the maximum flame adjustment of the valve.

In the operation of this preferred form of my improved valve construction, it will be evident that oil is maintained in the constant level chamber 4 at the level 4b which is sufficiently high to admit oil to the burner base but is below the top of the burner groove 67 so that flooding of the burner is impossible, even if the burner should go out. Also it will be clear that, as determined by the position of the plunger 26 in the plunger passage 20, oil will be supplied from chamber 4 through the passages 25, 24 and 23 past the needle 36 of the metering valve through passage 22 and annular groove 27 to the oil well 16 from which the oil is supplied to the burner through feed line 11. The maximum flow of oil is determined by the setting of the needle valve 36 and the minimum flow is determined by the vertical adjustment of the low flame abutment sleeve 33. It will be understood that the metering valve is adjusted to permit the maximum flow of oil which can be supplied to the burner without having the burner smoke and carbonize while the low flame adjustment by sleeve 33 is such that only a pilot flame is maintained in the burner.

In the position of the parts shown in Fig. 2, the control button 52 is in the defrost position, marked "0" on the dial, and consequently the stud 49 is in its uppermost position in which

the diaphragm 42 is relaxed and wafer 40 is elevated to enable the shoulder 32 on plunger 26 to engage the lower end of low flame adjusting sleeve 33, although the temperature responsive element 55 is at room temperature and wafer 40 is expanded. Defrosting continues with the burner B remaining on minimum flame until the control button 52 is rotated to an advanced position on the dial to cause stud 49 to depress the wafer 40 and with it the plunger 26. Assuming that control button 52 is rotated to its other extreme position, marked "5" on the dial, which represents the lowest temperature at which it is possible to maintain the refrigerating compartment, it will be evident that, due to the expanded condition of wafer 40, the control portion 28 of the plunger will move out of supply passage 22, supplying the burner B with the maximum amount of oil as determined by the setting of the metering valve 36. As the temperature in freezing unit 2 is lowered, the wafer will contract and shoulder 32 will ultimately engage the stop provided by sleeve 33, when the burner will burn with only a pilot flame. It will be understood that rotating the button 52 to an intermediate position on the dial will result in the engagement of shoulder 32 and sleeve 33 at a relatively higher temperature in the refrigerator compartment.

It will be evident from the above description that to install my improved thermostatically controlled valve A in existing refrigerators, it is only necessary to remove the manually controlled metering valve hitherto in use from the oil well 16 and replace it with the improved valve above described.

In adjusting the valve, the metering valve 36 is first adjusted with a plunger 26 depressed so that groove 27 registers with the outlet passage 22. In making this adjustment, the needle valve 36 is turned back away from seat 37a until the burner is supplied with the maximum amount of oil which it can consume without smoking. The plunger is then released and the low flame adjustment is made by turning the sleeve 33 until it engages the shoulder 32 at a point when the shoulder 29 is slightly below the point of cut off, permitting only a minimum flow of oil to the burner sufficient to maintain a pilot flame. The wheel 59 is then adjusted relative to the stem 51 to obtain the proper temperature setting for the thermostat. It will be evident that both the high flame and low flame adjustments can be varied in this construction without affecting the adjustment of the plunger by wheel 59 relative to the expansible wafer 40.

In Figures 5 and 5a I have shown a modified construction in which a valve casing 11a is provided, generally similar to casing 11, and in which the high and low flame adjustment means and the oil passage through the valve are similar but wherein the expansible member 40 has its supporting diaphragm 42 clamped between two annular rings 68 and 69 which are rotatably supported on a vertical standard 70 secured to the constant level float chamber 4. A transverse pin 70a in the standard 70 engages a groove 70b in a depending boss formed on ring 68, thus supporting the expansible member 40 in axial alignment over the plunger, a clamping nut 70c being provided on the upper end of the standard 70 which when loosened permits the expansible member 40 and its supporting means to be swung laterally out of the way and permit withdrawal of the plunger. In this construction there is no

positive connection between the plunger and the expansible member. Instead, an anvil 71 is adjustably screw threaded to the upper end of the plunger, thus providing for varying the temperature setting, the plunger rod having a flattened portion 72 which enables the rod to be held and the anvil 71 rotated relative thereto. A compression spring 73 surrounding the plunger bears at its lower end on the upper end of the low flame adjusting sleeve 33 and at its upper end on the anvil 71 fixed to the plunger, thus constantly urging the plunger against the expansible member 40.

In Figures 6, 7, and 8, I have shown a modified form of valve which may be used if desired. In this modified construction, the inlet passage 25 in valve casing 17b communicates directly with the plunger passage 20 and the plunger portion 26a is provided at its lower end with an axial passage 74 which communicates with a transverse passage 15, the ends of which terminate in the groove 27. Also in this construction a spring 73a is located beneath the plunger and acts against a shoulder 76 at the bottom of the plunger passage for constantly biasing the plunger upwardly into the position shown in Figure 6 in which the shoulder 32 engages the lower end of the low flame adjusting sleeve 33. The operation of this valve will be obvious from the description of the previously described forms.

In Figure 9 I have shown a modified construction which is applicable to any of the above forms of valve by which the upper screw threaded end of the reciprocable plunger can be directly connected by a ball and socket joint to the lower end of the expansible member 40. As shown in this figure, the lower end wall of the expansible member 40 is provided with a threaded boss 77 having a socket which is adapted to receive a ball 77a formed on the upper end of a threaded member 78 which corresponds to the anvils 71 shown in Figures 5 and 6, a cup-shaped holding member 79 being provided to hold the ball 77a in the socket while permitting free movement of the ball in the socket. This construction eliminates the necessity for springs 73 and 73a of Figures 5 and 6 and has definite advantages as hereinafter set forth.

In Figures 10-12 I have shown still another modified form of my improved thermostatically controlled valve A. As shown most clearly in Figure 12, the valve casing 17c comprises a piece of hexagonal stock, the lower threaded end 18 of which is provided with a small axial inlet passage 25 which communicates with an enlarged axial bore 80 threaded at its upper end at 81. The passage 80 constitutes a vertical plunger passage which communicates with the float chamber 4 through passage 25. The valve casing 17c also has a lateral oil passage 82 below the oil level 4b which communicates with the well 15 and the cross section of which is varied by the vertical reciprocable plunger, shown most clearly in Figure 11, as the latter is reciprocated in passage 80.

In this form of valve the plunger comprises a generally cylindrical tubular member 83 having an axial passage therethrough comprising a lower portion 85 of small diameter forming a valve seat 86a, an intermediate portion 86 of slightly increased diameter, and an upper portion 87 of still greater diameter providing an upwardly facing shoulder or spring seat 87a. A lateral passage 88 is provided in the plunger intersecting the axial passage therein just above the seat 86a and terminating in an external an-

nular groove 88a. This groove, as shown in Figure 11, is as wide or wider than the diameter of passage 82 in the valve casing with which it is adapted to be brought more or less into register when the valve is in open position. The lower cylindrical portion 89 of the plunger controls the outlet passage 82 of the valve by its upper edge 89a and is adapted to be a close but free running fit in the bore 80. The plunger 83 is also formed with an annular enlargement 90 intermediate its ends providing a shoulder 91 which cooperates with the lower end of an externally screw threaded sleeve 92 in which the plunger has a free running fit. The sleeve 92 has a hexagonal head 92a by which it is adjusted vertically in the upper screw threaded portion 31 of the valve casing 17c.

A metering valve is provided in the axial passage of plunger 83 comprising a stem 93 which is reciprocable in the upper enlarged portion 87 and a reduced needle portion 94 which cooperates with the valve seat 86a, a spring 95 located in the passage 87 between the spring seat 87a and the shoulder 96 on valve stem 93 constantly biasing the latter into engagement with a cam surface 97 on a transversely adjustable pin 98 which is threaded at 98a into the valve plunger 83. The pin 98 is provided with a radial spoke 99 by which it is rotated to move the cam surface 97 laterally and adjust the needle 94 relative to seat 86a, and is also provided with a fixed head 100 which prevents accidental removal of the pin. The axial passage in plunger 83 is threaded at its upper end to receive a vertically adjustable anvil 101, a lock nut 101a being provided to hold the anvil in adjusted position.

It will be evident from the above description that an oil passage is provided through the valve from float chamber 4 through the axial passages 25 and 85, and the transverse passages 88 and 82 to the well 15. It will also be evident that as the plunger 83 is reciprocated in the casing 17c the flow of oil through the outlet passage 82 will be varied as the annular groove 88a is brought into and out of register with passage 82.

The reciprocation of plunger 83 is governed by the expansible member 40 as described in connection with Figure 5, a spring 102 located in the bore 80 beneath the plunger constantly urging the plunger 83 upwardly into position to engage the shoulder 91 with the lower end of the low flame adjusting sleeve 92, as described in connection with previous forms.

In Figures 13 and 14 I have shown a modified form of concentric valve which may be used if desired. In this modified construction the valve casing 17c is the same but the plunger assembly, including the adjusting means for the metering valve, is wholly concentric with the casing. As shown in Figure 13, the metering valve 103 has an enlarged exteriorly threaded portion 103a which is threaded into an axial passage 104 in the plunger to adjust the needle valve relative to the seat 86a, a hexagonal wrench engaging portion 105 being provided at its upper end. A lock nut 105a is provided for clamping the valve 103 in adjusted position. To assist in holding the plunger during adjustment of the metering valve 103, diametrically opposed flat portions 106 (Figure 14) are provided at the upper end of the plunger adjacent the clamping nut 105a. A vertically adjustable anvil 107 is

threaded into the upper end of the valve 103 and engages the wafer 40.

The operation of the valve of this modified construction is similar to those above described, the high flame adjustment being made by rotating the metering valve 103 in the screw threaded passage 104 of the plunger and the low flame adjustment being made by rotating the abutment sleeve 92.

In Figure 15 I have shown a construction for directly connecting the plunger to the expandible member 40, somewhat similar to that shown in Figure 9 except that the ball carrying member corresponding to member 78 to Figure 9 is externally screw threaded to take the place of anvils 101 and 107 of Figures 10 and 13 respectively.

The direct connection of the plunger to the expandible fluid operated member 40 is highly desirable, and for this reason the constructions shown in Figures 5, 6, 10 and 13, in all of which the plunger is actuated in one direction by a spring, are not preferred. The elimination of the spring against which the expandible member must work when expanding, has been found to result in a more sensitive operation of the valve, enabling closer temperature regulation. Further, when a spring is used, the amount of expandible fluid in the element 55 and member 40 varies with the tension of the spring against which the member 40 must expand, thus requiring matching of the spring and the expandible fluid in the thermostat which is very objectionable from the manufacturing standpoint and altogether eliminated in my preferred direct connected plunger constructions.

It will be evident that as a result of my invention it is possible for the first time to provide automatic temperature governed fuel control for oil burning refrigerators in which it has been hitherto necessary to use manual fuel control. Attention is further directed to the fact that this new result is obtained while enabling the burner to operate effectively at all temperatures while obtaining certain of the improved results set forth in my copending applications and without irregularities in the flame such as would result from the use of a drip feed or devices requiring the raising and lowering of the oil supply. Further, as a result of my improved valve constructions, a unitary thermostatically controlled valve structure is provided including the temperature responsive control valve and the high flame metering valve, which is adapted to be substituted for the manually controlled valve furnished with existing oil burning refrigerators. It will also be noted that in various of the improved constructions above described the fuel control valve is actuated directly by and moved with the expandible member during expansion and contraction of the latter, increasing the supply of fuel to the burner as the expandible member expands. It will also be evident that in certain forms of my improved construction I have provided such a unitary valve structure in which the metering and temperature controlled valves are concentric and which is adapted to be manufactured quickly and cheaply by well known automatic screw machine processes. These and other advantages of my improved construction will, however, be apparent to those skilled in the art.

While I have in this application specifically described several embodiments of my invention, it will be understood that these are shown for

illustrative purposes and that the invention may be modified and embodied in other forms without departing from its spirit or the scope of the appended claims.

What I claim as new and desire to secure by Letters Patent is:

1. In a thermostatically controlled valve, an axially elongated valve casing insertable longitudinally in a substantially corresponding longitudinal socket and having an exposed upper end, said casing having a lower fuel inlet and a communicating transverse fuel supply passage extending transversely therein, means for controlling the supply of fuel through said passage including a valve member extending inside said casing and adjustable longitudinally thereof to vary the effective cross section of said transverse supply passage, temperature responsive means for operating said valve member, and manually operative valve means disposed longitudinally of said casing having a control portion inside said casing also controlling the amount of fuel which can be supplied through said transverse supply passage, said valve member and valve means each having adjusting means extending above the exposed upper end of said casing and adjustable following insertion of the latter in said socket.

2. In a thermostatically controlled valve, an axially elongated valve casing insertable longitudinally in a substantially corresponding longitudinal socket and having an exposed upper end, said casing having a lower fuel inlet and a communicating transverse fuel supply passage extending transversely therein, temperature responsive means for controlling the quantity of fuel supplied through said passage including an expandible fluid operated member and a movable valve member extending inside said casing and adjustable longitudinally thereof by said member to control the effective cross section of said transverse supply passage, said valve member having means adjustable from the upper exposed end of said casing for limiting the movement of said movable valve member in one direction whereby to maintain a minimum fuel supply through said transverse passage, and a metering valve disposed longitudinally of said casing having a control portion within said casing and also having a portion outside said casing adjustable from said end of said casing for adjusting said control portion to limit the quantity of fluid which can be supplied through said supply passage.

3. In a thermostatically controlled valve, an axially elongated casing insertable longitudinally in a substantially corresponding longitudinal socket and having an exposed upper end, said casing having a lower fuel inlet and a communicating transverse fuel supply passage extending transversely therein, temperature responsive means at one end of said casing for controlling the quantity of fuel supplied through said passage including an expandible fluid operated member and a plunger operated by said member and intersecting said transverse supply passage and having a reduced portion adjacent its lower end forming a shoulder on said plunger above the lower end of said plunger adapted to be moved across said transverse supply passage to vary the effective cross sectional area thereof, and means disposed above the exposed upper end of said casing and adjustable following insertion of said casing in said socket for limiting the amount of fuel supplied through said passage, and means likewise projecting above the upper end of said casing and independently adjustable relative to

said plunger for insuring a minimum orifice in said supply passage.

4. In a thermostatically controlled valve, an axially elongated valve casing insertable longitudinally in a substantially corresponding longitudinal socket and having an exposed upper end, said casing having a lower fuel inlet and a communicating transverse fuel supply passage extending transversely therein, temperature responsive means for controlling the quantity of fuel supplied through said passage including an expansible fluid operated member and a valve plunger extending inside said casing and adjustable longitudinally thereof and having a controlling portion inside said casing adapted to be brought into and out of register with said supply passage in response to movements of said plunger, and an axial sleeve adjustably carried by the exposed upper end of said casing through which said plunger is movable and located between the upper end of said casing and said expansible fluid operated member and engageable with said plunger for limiting the movement of said plunger in one direction whereby to maintain a minimum fluid flow through said communicating passages.

5. In combination, a constant level fuel chamber having a vertically elongated socket, valve mechanism for controlling the flow therefrom including an axially elongated valve casing insertable longitudinally into said socket with its lower end in fluid communication with said chamber below the level of fuel therein and its upper end projecting above the top of said chamber, said mechanism having an axial inlet passage, an outlet passage and an intermediate transverse fuel supply passage all located below said level, temperature responsive means for controlling the supply of fuel through said supply passage including an expansible fluid operated member located above the upper end of said valve casing and a valve member movable therewith and extending inside said casing to vary the effective cross-section of said supply passage, manually operable valve means having a control portion inside said casing for limiting the amount of fuel which can be supplied through said supply passage, means on the upper projecting end of said valve casing for effecting axial adjustment of said valve member, and means also accessible from the exposed upper end of said valve casing for adjusting said valve means while said mechanism remains in said chamber.

6. In a thermostatically controlled valve, an axially elongated valve casing insertable longitudinally in a substantially corresponding longitudinal socket and having an exposed upper end, said casing having a bottom axial inlet, a communicating transverse fuel supply passage and a plunger passage intersecting said transverse supply passage, a valve plunger in said plunger passage having an annular groove intermediate its ends, an expansible fluid actuated member located above and actuating said plunger to bring its groove into and out of register with said transverse passage in said casing, adjustable means located on the exposed upper end of said casing between the groove on said plunger and said expansible member for limiting the movement of said plunger in one direction whereby to prevent complete closure of said supply passage by said plunger, and a metering valve located in said casing alongside said plunger passage and controlling the cross section of said supply passage independently of the control thereof by said

plunger and also accessible for adjustment at the exposed upper end of said valve casing following insertion of the latter in the socket.

7. In a thermostatically controlled valve, an axially elongated valve casing insertable longitudinally in a substantially corresponding longitudinal socket and having an exposed upper end, said casing having an axial fuel inlet and a communicating transversely extending supply passage at one end thereof, two control passages located alongside each other in said casing and both intersecting said supply passage, a manually adjustable metering valve in one of said control passages projecting above the upper exposed end of said casing and at its other end controlling said supply passage, and an expansible fluid actuated valve member in the other control passage having a portion movable across said supply passage to govern the effective cross-section thereof in response to temperature changes affecting said expansible fluid.

8. In a thermostatically controlled valve, an axially elongated valve casing insertable longitudinally in a substantially corresponding longitudinal socket and having an exposed upper end, said casing having an axial fuel inlet and a communicating transversely extending supply passage at one end thereof, two control passages located along side each other in said casing and both intersecting said supply passage, a manually adjustable metering valve in one of said control passages having its lower end movable into said supply passage and having its upper end projecting above the exposed upper end of said valve casing, and an expansible fluid actuated valve member in the other control passage having a portion movable across said supply passage to govern the effective cross-section thereof in response to temperature changes affecting said expansible fluid, and means located at the upper exposed end of said valve casing concentric with said valve member and adjustable relative to said casing for limiting the movement of said valve member in one direction whereby to maintain a minimum orifice through said supply passage at said expansible fluid operated valve.

9. In a thermostatically controlled valve, an axially elongated valve casing insertable longitudinally in a substantially corresponding longitudinal socket and having an exposed upper end, said casing having an axial fuel inlet and a communicating transversely extending supply passage therein adjacent its lower end, a plunger passage intersecting said supply passage, a plunger reciprocable in said plunger passage having a portion movable across said supply passage to control the effective cross-section thereof, an expansible fluid operated member acting on the upper end of said plunger having a supporting frame, a manually adjustable metering valve also controlling the cross section of said transverse supply passage and disposed in parallel relation to said plunger and projecting above the exposed upper end of said valve casing, and a rigid support for said frame carried by the exposed upper end of said valve casing and having an axial passage therethrough into which said plunger and metering valve project.

10. In a thermostatically controlled valve, an axially elongated valve casing insertable longitudinally in a substantially corresponding longitudinal socket and having an exposed upper end, said casing having an axial fuel inlet and a communicating transverse supply passage therein adjacent its lower end, a plunger passage inter-

secting said supply passage, a plunger reciprocable in said plunger passage having a portion movable across said supply passage to control the effective cross section thereof, an expansible fluid operated member located above said plunger having a supporting frame, adjustable means located between said member and said plunger for varying the effective length of said plunger, a manually adjustable metering valve also controlling the cross section of said supply passage and disposed in parallel relation to said plunger and projecting above the exposed upper end of said valve casing, and a rigid support for said frame surrounding said plunger and metering valve and carried by said valve casing and having a portion cut away between said valve casing and supporting frame to permit access to the upper end of said metering valve and to said adjustable means.

11. In a thermostatically controlled valve, an axially elongated valve casing insertable longitudinally in a substantially corresponding longitudinal socket and having an exposed upper end, said casing having an axial fuel inlet and a communicating transverse supply passage therein adjacent its lower end, a plunger passage intersecting said supply passage, a plunger reciprocable in said plunger passage having a portion movable across said supply passage to control the effective cross section thereof, an expansible fluid operated member acting on said plunger having a supporting frame located above said plunger, adjustable means carried by the exposed upper end of said valve casing and concentric with said plunger for limiting the extent of movement of the latter in one direction, and a rigid support for said frame carried by said valve casing and surrounding said plunger and adjustable means and having a portion cut away to permit access to said adjustable means.

12. In a thermostatically controlled valve, an elongated valve casing having a supply passage therein adjacent its lower end, a plunger passage intersecting said supply passage, a plunger reciprocable in said plunger passage having a portion movable across said supply passage to control the effective cross section thereof, an expansible fluid operated member connected to the upper end of said plunger having a supporting frame, adjustable means located between said frame and said valve casing for varying the effective length of said plunger, a metering valve also controlling the cross-section of said supply passage, and a rigid support surrounding said plunger and connecting said frame and valve casing having an intermediate portion cut away to permit access to said metering valve and said adjustable means.

13. In a thermostatically controlled valve, a valve casing having a transverse fuel supply passage therein, a plunger passage intersecting said supply passage, a valve plunger movable in said plunger passage having a portion adjacent its lower end controlling the effective cross section of said supply passage, low flame adjusting means coaxial with said plunger and extending above the latter for limiting the upward movement of said plunger and maintaining a minimum orifice in said supply passage, and expansible fluid actuated means supported above said plunger for moving said plunger away from said low flame adjusting means to increase the cross section of said supply passage in response to increases in temperature affecting said fluid.

14. In a thermostatically controlled valve having a fuel supply passage, temperature respon-

sive means for controlling the supply of fuel through said passage including an expansible fluid operated member and a valve member movable therewith to control said passage, and a 5 metering valve within said valve member also controlling the supply of fuel through said supply passage.

15. In a thermostatically controlled valve having a fuel supply passage therethrough, temperature responsive means for controlling the supply of fuel through said passage including an expansible fluid operated member and a plunger movable with said member to vary the effective cross-sectional area of said passage, and a metering valve including a manually adjustable valve member within and coaxial with said plunger also adjustable to vary the supply of fuel through said supply passage.

16. In a thermostatically controlled valve having a fuel supply passage therethrough, temperature responsive means for controlling the supply of fuel through said passage including an expansible fluid operated member and a plunger reciprocated by and movable in the same direction with said member to vary the effective cross section of said passage, said plunger having a vertical passage and a horizontal passage communicating with said supply passage, and means coaxial with said plunger and extending into said vertical plunger passage for limiting the amount of fuel supplied through said passage.

17. In a thermostatically controlled valve, a valve casing having a lateral oil supply passage and a plunger passage extending transversely of said supply passage, temperature responsive means controlling said supply passage including an expansible fluid operated member and a plunger reciprocable in said plunger passage in response to expansion and contraction of said member and having fluid passage means therein adapted to be brought into register with said supply passage to control the fluid supplied therethrough, and a manually adjustable needle valve carried by said plunger and controlling the cross section of said fluid passage means.

18. In a thermostatically controlled valve, a valve casing having a lateral oil supply passage and a plunger passage extending transversely of said supply passage, temperature responsive means controlling said supply passage including an expansible fluid operated member and a plunger reciprocable in said plunger passage in response to expansion and contraction of said member and having fluid passage means therein adapted to be brought into register with said supply passage to control the fluid supplied therethrough, a needle valve carried by said plunger and vertically reciprocable relative thereto to vary the cross section of said fluid passage means, cam means for reciprocating said needle valve, and manually operable means external of said plunger for actuating said cam means.

19. In a thermostatically controlled valve, a valve casing having a transverse oil supply passage and a vertical plunger passage extending transversely of the same, temperature responsive means controlling said supply passage including an expansible fluid operated member and a plunger reciprocable in said plunger passage having communicating vertical and transverse passages, the latter adapted to be brought into register with said supply passage to control the fluid flow through the latter, a needle valve adjustable in said vertical plunger passage controlling the

cross section of said passage, and means for adjusting said needle valve including an operating member located transversely of said plunger above said needle valve and having cam means within the vertical plunger passage acting on said needle valve.

20. In a thermostatically controlled valve, a valve casing having a transverse oil supply passage and a vertical plunger passage extending transversely of the same, temperature responsive means controlling said supply passage including an expansible fluid operated member and a plunger reciprocable in said plunger passage having communicating vertical and transverse passages, the latter adapted to be brought into

register with said supply passage to control the fluid flow through the latter, a needle valve adjustable in said vertical plunger passage controlling the cross section of the latter, means for adjusting said needle valve including an operating member located transversely of said plunger above said needle valve and having cam means within the vertical plunger passage acting on said needle valve, and means carried by said plunger above said operating member and vertically adjustable relative to said plunger having an operative connection with said expansible fluid operated member.
